STENCIL APPARATUS FOR FLATWARE
DECORATING

Howard P. Fischer, Monaca, Pa.

Application October 29, 1948, Serial No. 57,213

1 Claim. (Cl. 101—126)

1 This invention relates generally to ware decorating and more particularly to improvements in screen stenciling apparatus for decorating flatware.

This invention contemplates the provision of a flatware decorating machine having an adjustable guideway for conducting a multiple series of articles under a hinged screen carrying a stop which functions as a gauge when the screen is in stenciling position to properly position the articles relative to the stencils on the screen and which allows the articles to pass through the machine when the screen with the stop is raised. This structure provides a simple apparatus that is very economical in stenciling an extremely high production of flatware with one sweep of the squeegee across the multiple printing screen decorating three or more dozen pieces at a time and the structure required is inexpensive and easily constructed.

Other objects and advantages appear in the following description and claim.

Practical embodiments illustrating the principles of this invention are shown in the accompanying drawings wherein:

Fig. 1 is a perspective view of a multi-series flatware decorating machine of the simplest form;

Fig. 2 is a perspective view of a modified form of multiseries flatware decorating machine comprising this invention with parts broken away;

Fig. 3 is a plan view of the structure shown in Fig. 2 with parts broken away;

Fig. 4 is a front elevation of the structure shown in Fig. 2;

Fig. 5 is a rear elevation of the structure shown in Fig. 2; and

Fig. 6 is an end elevation of the structure shown in Fig. 2.

Referring principally to Fig. 1 of the drawings the base 1 of the machine is provided with the spaced parallel guides 2 and 3, the guide 3 being adjustable through the relocation of the brackets 4 secured by the wing nuts 5 in the several holes 6. Similar tracks or guideways 7 and 8 are employed at the feed and discharge ends, respectively, of the machine for the purpose of receiving articles such as the flat-sided bottles 10 and sliding the same through the machine.

At the rear of the base 1 the machine is provided with a pair of upstanding posts 11 to which the forwardly extending arms 12 are hinged as indicated at 13. The posts 11 may be positioned at different relative heights by means of changing the location of the fastening bolts 14. This

permits raising or lowering of the hinge 13 relative to the upper surface of the base 1. The spaced arms 12 are provided with the wing fastening means 15 which secure the framed screen member 16 to the underside of the arms causing them to function as a unit. The screen member 16 is provided with a wooden rectangular frame 17, the under surface of which has attached thereto the fine mesh screen 18, on which is positioned a plurality of stencils 19. Each stencil is accurately located on the screen so as to properly align the designs with their respective flatware articles 10 indicated as the small flat-sided bottles on the drawings. The screen mesh 18 may be of silk, plastic, wire or other suitable mesh and the stencils 19 may be affixed thereto by any suitable method such as the photographic method well known in the ware decorating art.

The guide rail 3 is provided with a pair of upwardly extending stop posts 20 that may be adjusted for different heights relative to the articles and is arranged to be engaged by the outer or free end of the hinged screen member 16 when the latter is in its horizontal position. When the screen 16 is lowered to a horizontal position, so as to rest on the top posts 20, the surface of the screen lies a short distance above the surface of the articles 10.

The right end of the screen 16, which represents the discharge end of the machine, is provided with a lateral stop strip 21 which, when the screen is lowered to its horizontal stenciling position, is disposed in the path of movement of the bottles 10. Thus, when the screen is lowered so as to rest on the vertically adjustable posts 20 the bottles 10 may be shoved under the screen between the guideways 2 and 3 until their necks or forward ends engage the transverse stop 21 on the underside of the screen. This stop is fastened to the screen in such a manner as to properly align each series of bottles relative to the rows of stencils 19 on the screen. It is preferable that the operator manually move the series of bottles until they engage the stop 21 although there may be several bottles at the feed end of the machine engaging the bottles within the machine, the former being unable to be fed into the machine unless the hinged screen 16 is raised to allow the other bottles to pass out of the machine.

50 A pigment is placed on the top surface of the screen 18 and a hand squeegee is employed to move the pigment from one end of the screen to the other. It is found in operation that the screen may be made sufficiently large to cover as many as four series of articles, each series con-

taining as many as a dozen small bottles all of which may be decorated by a single sweep of the squeegee in one direction. After the bottles are decorated the hinged screen is raised to lift the stop 21 from the path of the bottles and the bottles are then moved through the machine until the last decorated bottle is up to the stop 21 at which time the operator moves the decorated bottles out of the road and down the discharge guireway 8 and permits the screen to be lowered so that the stop 21 again operates to arrest and align the next set of multiple series of flat articles.

The structure shown in Figs. 2 to 6 is more elaborate than that shown in Fig. 1 and is capable of decorating a considerably greater number of articles with a single sweep of the squeegee than that of the structure of Fig. 1. The article receiving base 22 is provided with the upwardly extending guides 23 and 24. The back guide 23 may be formed integral with the base and the guide 24 may be conveniently made from an angle iron which is adjustable relative to the rear guide 23. The base 22 is supported on the side channel members 25 and 26, the outer side of which is provided with the transverse angle irons 21 for supporting the tracks or guideways for supplying and discharging the ware from between the guideways on the base plate 22 and either end of the machine.

The base 22 is provided with spaced horizontally disposed rearwardly extending posts 28, as shown in Figs. 2, 3, 5 and 6, arranged to receive the blocks 29 which are adjustably secured and slidably therealong and carry the vertically adjustable standards 30 having bearing members 31 secured at the upper ends of the latter. The bearings 31 carried by each of the spaced standards are aligned with one another to receive the shaft 32 on which is journaled the arms 33 and 34, at either end of the machine and which are adjustably secured therealong. The arms 33 and 34 extend forwardly and rearwardly of the bearings 31 as shown at 35 and their rearward portions are provided with an outwardly extending pin 36 rotatably mounted in the arms 35 and arranged to receive and clamp onto their respective pitman rods 37. The other end of the pitman rods are pivotally attached to the one arm of the bell crank levers 38. The spaced bell crank levers 38 are each pivotally supported on their respective support members 25 and 26 as indicated at 39. The other arm of each of the bell crank members is pivotally attached to an actuating rod 40, the front ends of which extend to the front of the machine and are connected to the arcuate bumper rod 41. The weight of the screen assembly is partially counterbalanced by the springs 42 on each of the rods 40 but will not raise the arms 33 and 34 from their horizontal positions. By depressing the bumper rod 41 the bell crank levers 38 in Fig. 6 oscillate in a counter-clockwise direction causing the pitman rods 37 to pull down on the rear ends of the arms 33 and 34 causing them to pivot on the shaft 32 and thereby swing them up from the base 22. The blocks 29, being adjustable to and away from the base 22 on the rods 28, and the standards 30 being adjustable in the blocks 29, and the pitman rods 37 being adjustably secured in the pins 36, permits the bearings 31 to adjust the shaft 32 in different positions relative to the base so as to permit the machine to receive ware of different dimensions.

Each of the arms 33 and 34 is provided with

a pair of spaced upstanding posts 42. The opposed posts on the arms 33 and 34 are provided with aligned openings for receiving the front and rear track rods 43 and 44. Thus, the arms 33 and 34 and rods 43 and 44 form a unitary rectangular frame. Each of the arms 33 and 34 are provided with the slots 45 for receiving the screws 46 which hold the screen frames 47 on the underside thereof. The slots 45 permit the screen 47 to be adjusted laterally of the guides 23 and 24 and the arms 33 and 34 are adjustable along the shaft 32 and the rods 43 and 44 to make the rectangular frame formed by the arms and rods to correspond with the length of the screen 47. However, the track rods 43 and 44 are not adjustable relative to each other as they function as track members for the squeegee carriage 48.

In order to properly support the screen frame 47 in its horizontal decorating position a pair of block members 50 are adjustably secured to the front of the base 22 and are provided with vertically adjustable arms 51 arranged to engage the underside of the screen frame 47 and maintain the same horizontal relative to the adjustable position of the shaft 32 at the rear of the machine.

As shown more clearly in Figs. 2 and 4, the arm 34 is provided with the spaced depending brackets 52 which carry the spaced parallel arms 53 that extend toward the arm 33. Each of the arms 53 is provided with a slot for receiving the adjustable stop bar member 54 which lies transversely underneath the screen member 47 and may be disposed at right angles to the guideways 23 and 24 between which the articles travel and in the path thereof, when the screen is disposed in its horizontal position as shown. When the bumper rod 41 is depressed and the arms 33 and 34 are hinged to raise the screen the stop bar 54 is also raised and withdrawn from the path of the articles permitting them to be moved through the machine. Thus, the stop bar 54 may be adjustably positioned relative to the screen rather than being secured to the screen as disclosed with reference to the structure shown in Fig. 1.

The squeegee carriage 48 consists of the side frame members 55 and 56 connected by the rods 57 and each is provided with a set of five wheels, each of which are grooved to fit the rods 43 and 44. Two of the wheels 58 bear on the top of the rail rods to support the weight of the squeegee. A third wheel 59 bears on the underside of the rods to prevent the squeegee carriage from being raised from the track. A pair of wheels 60 are disposed on vertical axes for engaging the inner side of the rods for the purpose of aiding in maintaining the alignment of the carriage as it moves from one end of the track to the other above the screen frame.

The squeegee carriage side frame members 55 and 56 are provided with spaced upwardly extending lugs 61 and 62 for receiving the ends of the beam 63. One end of the beam 63 is pivotally attached between the lugs 61 and the other end is slidably between the lugs 62 and is biased to be raised by the spring 64, the tension of which may be varied by the screw 64.

The beam 63 is provided with the slot 65 for slidably receiving the squeegee holder 66 which is provided with an upwardly extending bifurcated arm 67 that fits on both sides of the beam 63 and is provided with a shaft 68 extending through the slot 65 arranged to carry a roller

that operates therein. The underside of the squeegee holder 66 is provided with a longitudinal slot 70 for receiving the squeegee in interlocking engagement. The squeegee may be held in place by a transverse pin 71. The beam 63 thus may be lifted to raise the squeegee up out of the carriage and permit the same to be removed or replaced. It is of course necessary for the operator to depress the beam 63 against the pressure of the spring 64 in order to permit the blade of the squeegee to engage the upper surface of the screen for the purpose of forcing decorating material therethrough. As the operator presses down on the outer end of the beam 63 he is enabled to move the carriage from one end of the frame to the other and thus cause the squeegee to sweep the pigment through the screen onto all of the articles lying on the base 22. When the screen is provided with a multiple series of stencils, each stencil being made in alignment and properly spaced from one another in accordance with the dimensions of the articles, and placed on the underside of the frame, the stop 54 is then adjusted so as to accurately position each of the articles when engaging one another in tandem directly beneath its respective stencil in the screen. The operator then applies a pigment or decorating material to within the frame of the screen and sweeps the squeegee carriage from one end of the frame to the other while depressing the squeegee into contact with the upper surface of the screen causing the latter to flex downwardly and engage each of the articles to deposit a decoration thereon. At the end of the stroke the operator presses on the bumper rod 41 with his body, causing the frame to hinge on the shaft 32 to raise the stop and permit the articles to be moved through the machine. As the frame is hinged upwardly the decorating material will run to the rear end of the screen but the latter will not be tilted sufficiently high to permit the material to escape or be lost therefrom. While the screen is in its raised position the operator may easily push the decorated ware past the stop 54 and then permit the screen to again drop to its horizontal position

placing the stop 54 in the path of the next set of articles being shoved into the machine.

As shown in Figs. 5 and 6, directly below the stop 54 the machine is provided with a foot treadle 74 arranged to actuate the rod 75 which is pivotally secured to the outer end of the lever 76 arranged to hinge on the fulcrum 77. The lever is provided with a stop blade 78 arranged to extend upwardly into the path of the articles 10. Thus, as the undecorated articles are moved through the machine the operator is enabled to press the treadle 74 and cause the stop 78 to rise into their path and permit the screen to be lowered to its decorating position. The articles 15 may then be shoved forward to engage the stop 54 and become properly aligned with the stencils on the screen, ready to receive their decorations.

I claim:

20 In an article decorating apparatus, the combination of a guideway along which a multiple series of articles may travel through the apparatus, a screen frame having a screen with a multiple series of stencils formed thereon in positions matched with the positions of articles to be placed on the guideway, hinge means adjacent the guideway for receiving the screen frame and to maintain proper alignment of the stencils of the screen relative to articles on the guideway, 25 30 35 and a unitary stop means extending transversely of the guideway and carried by the screen frame to arrest and gauge the position of the articles on the guideway when the hinge means maintains the screen in stenciling position and to release the articles for movement along the guideway when the screen and frame are raised from the stenciling position.

HOWARD P. FISCHER.
